UNITED STATES PATENT OFFICE.

JOHN LOCKHART, OF TARRYTOWN, NEW YORK.

WINDOW-SHUTTER.

1,149,273.

Specification of Letters Patent.

Patented Aug. 10, 1915.

Application filed December 1, 1914. Serial No. 874,957.

To all whom it may concern:

Be it known that I, JOHN LOCKHART, a citizen of the United States, and residing at Tarrytown, in the county of Westchester and State of New York, have invented certain new and useful Improvements in Window-Shutters, of which the following is a specification, such as will enable those skilled in the art to which it appertains to make and use the same.

This invention relates to window shutters, and the object thereof is to provide shutters of this class which may be used as awnings, said shutters being adapted to be swung out at the bottom thereof in planes at right angles to the windows or the walls of the building in which the windows are placed, and being also provided with supplemental side members which close the side spaces when the bottoms of said shutters are swung outwardly; and with this and other objects in view the invention consists in the construction, combination and arrangement of parts hereinafter described and claimed.

The invention is fully disclosed in the following specification, of which the accompanying drawing forms a part, in which the separate parts of my improvement are designated by suitable reference characters in each of the views, and in which:—

Figure 1 is a vertical section through one side portion of a window frame provided with a shutter made according to my invention, part of the shutter construction being broken away and part being shown in section, and the shutter being swung outwardly as when used as an awning; Fig. 2 a transverse sectional view showing the shutter closed; Fig. 3 a transverse sectional view of a part of one of the supplemental shutter members and on an enlarged scale; and, Fig. 4 a partial section on the line 4—4 of Fig. 1.

In the accompanying drawing, I have shown my improvement applied to a form of shutter described and claimed in U. S. Letters Patent granted to me October 21, 1913, No. 1,076,637, and which involves a shutter *a* hinged to a top shutter member *b* and adapted to be swung outwardly as shown in Fig. 1, and the construction and arrangement of which is such that when the shutter *a* and top shutter member *b* are both in a closed position they may be secured together and swung laterally into an open position in the manner of an ordinary shutter.

I have also shown in the accompanying drawing a window frame comprising a top member *c*, a bottom member *c*² and side members *c*³, only one of which is shown, and mounted in said frame are the usual top and bottom sashes *d* and *d*².

In the practice of my invention I form in the back of the outer side *a*² of the shutter *a* a vertical groove or opening *a*³, and provide a side supplemental shutter member *e* made in the manner of a fan and comprising a plurality of blades *e*² pivoted together at the top end thereof and also pivoted in the corresponding end of the groove or opening *a*³ as shown at *e*⁹.

The blades *e*² of the supplemental shutter member *e* are connected by a chain or other flexible device *e*⁴, each of said blades being provided with eye-plates or similar devices *e*⁵ which are riveted thereto, as shown at *e*⁶, and with which the chain *e*⁴ or other flexible device is connected, and this prevents the separation of the blades *e*² in the operation of opening and closing the supplemental shutter member *e* as will be readily understood.

One side edge blade member *e*² of the supplemental shutter member *e* is provided with a transverse slot *e*⁷ through which is passed a pin, screw or similar device *e*⁸ whereby said supplemental shutter member *e* is secured to one of the side walls of the groove or opening *a*³ in the outer frame member *a*² of the shutter *a*, and the opposite side blade member *e*² of the supplemental shutter *e* is provided with a pivoted hook or similar device *e*⁹ adapted to engage an eye-pin or screw *e*¹⁰ secured to the window sash, and by means of this construction, when the shutter *a* is swung outwardly the supplemental shutter member *e* will be opened so as to close the space between the shutter *a* and the window frame at the outer side of said shutter, and when the shutter *a* is dropped into the closed position, the said supplemental shutter member *e* will be collapsed into the groove or opening *a*³, as shown in Fig. 2, and pivoted to the inner side of the shutter frame member *a*² is a catch *e*¹¹ adapted to hold the separate parts of the supplemental shutter member *e* in a closed position.

Secured to the sides of the window frame is a vertically arranged bar *f* and mounted thereon and vertically movable thereon is an arm *g* which is loosely connected with

the lower end of the shutter a at g^2 , and when the shutter a is swung outwardly as shown in Fig. 1 the inner end of the arm g moves upwardly on the bar f and said bar 5 folds downwardly, this construction and the operation thereof being the same as in the patent referred to.

While I have shown my improvement applied to but one shutter, it will be understood that, in practice, said improvement is 10 applied to both shutters, and while I have shown and described my improvement applied to a shutter a hinged to a top shutter member b it will be understood that the 15 employment of the top shutter member b is not necessary and my improvement may be applied to any shutter constructed and arranged to be swung outwardly at the bottom thereof so as to adapt said shutter 20 to serve as an awning, and with my improvement either or both the shutters of a window may be swung outwardly and held in the position shown in Fig. 1 of the accompanying drawing, and when so used the 25 space or spaces between the shutter or shutters at the sides of the window frame will be closed and all side drafts and rain will be prevented from entering the window between the sides of the shutters and the sides 30 of the window frame.

In the accompanying drawing, the shutter a is provided at the bottom thereof with a hinge member h adapted to engage a corresponding hinge member on the side of the 35 window frame when the shutter a is in a closed position and the shutter member b is also connected with the frame by a hinge h^2 , this construction being the same as in the patent referred to, and when the shutter 40 a is in the closed position the hinge member h engages the corresponding hinge member connected with the window frame, but not shown, and the shutter a is secured to the

shutter member b and forms in connection therewith the complete shutter which is 45 adapted to be swung outwardly in the manner of other devices of this class.

Having fully described my invention, what I claim as new and desire to secure by Letters Patent, is:—

50

1. A window shutter adapted to be swung outwardly at the bottom thereof and provided in the side of the frame thereof with a longitudinal groove or opening in the top of which is pivoted a supplemental side 55 shutter member made in the form of a fan and the separate parts of which are adapted to open up so as to close the space between the shutter and the window frame when the bottom of the shutter is swung 60 outwardly.

2. A window shutter adapted to be swung outwardly at the bottom thereof and provided in the side of the frame thereof with a longitudinal groove or opening in the top 65 of which is pivoted a supplemental side shutter member made in the form of a fan and the separate parts of which are adapted to open up so as to close the space between the shutter and the window frame 70 when the bottom of the shutter is swung outwardly, and means for connecting the parts of the supplemental shutter member and connecting one side edge portion of said shutter member with the main shutter 75 frame and the other with the window frame.

In testimony that I claim the foregoing as my invention I have signed my name in presence of the subscribing witnesses this 80 30th day of November 1914.

JOHN LOCKHART.
